SUPPORTING MEANS FOR GIRDERS
OR THE LIKEJohn William Pratt, Leicester, England, assignor
to Fossain-Wycliffe Foundries, Limited, Lutter-
worth, EnglandApplication April 12, 1950, Serial No. 155,510
In Great Britain August 23, 1948

9 Claims. (Cl. 248—228)

1

This invention relates to supporting means for girders or the like, and concerns more particularly, but by no means exclusively, so-called "horseheads" for underslinging safety girders in coal mines. The term "horsehead" is used in the coal mining industry to indicate a mechanical device by means of which a girder can be suspended from another girder.

Horseheads are used in coal mines to support a portion of the roof at the coal face, which roof portion is formed by the under-cutting and shot-firing of the material at the gate road end or lip, or may be formed where back ripping of the roof of the road leading up to the coal face or other roads is taking place.

When coal and other material which has already been loosened has been cleared away at the lip or ripping the lip or roof, then to be ripped, is drilled and a shot or shots is or are fired near the top of the roof mainly in the stone. This brings down a mass of material and leaves the roof above the mass unsupported and likely to fall.

To prevent material from falling from the roof onto the miners when they are removing the coal and other material from the mass it is desirable to provide support for the roof above the mass. Further, the roof above the roadways, although supported, usually by props and cross-girders, sinks in course of time until it becomes too low and it is then necessary to remove some of the roof to increase the height of the roadway. When part of the roof has been removed it becomes essential temporarily to support the new roof until the cut away material is removed from beneath it and permanent supporting means can be placed in position.

The general object of the present invention is to provide improvements in girder-supporting means, as will be hereinafter described.

A particular aim is the provision of improved horseheads adapted for use in temporarily supporting roof portions of roadways or other parts of a mine.

The girder-supporting means of this invention comprise members provided with jaw portions adapted for engagement with a girder, the said members having pivotal connection with one another and being themselves adapted to support another girder.

In order that the invention may be more clearly understood and readily carried into practical effect, specific examples of horseheads constructed in accordance therewith will now be described with reference to the accompanying drawings, wherein,

2

Figure 1 is an elevation of one form of horsehead shown in position on a cross-girder, and in turn supporting a safety girder.

Figure 2 is a side elevational view of the same as seen in the direction of the arrow A in Figure 1.

Figure 3 is a part-sectional plan view corresponding to Figures 1 and 2.

Figure 4 is a detail cross-sectional view taken on the line IV—IV in Figure 1, and

Figures 5 and 6 are views corresponding to Figures 1 and 2 respectively illustrating a further form of horsehead which can be made up of castings.

15 Like parts are designated by similar reference characters throughout the drawings.

The illustrative horsehead depicted in Figures 1 to 4 comprises two U-shaped members 1 and 3 each of which is formed by bending a single piece of material. The member 1 has two spaced arms 5, 5 which extend upwardly and have at their upper ends hooked jaw portions 5a adapted to engage over one edge of the lower flange 7 of a cross or arch girder 9. Each arm 5 has in it a recess 11 extending inwardly from the inner face 13 of the said arm. The depth of the recess 11 is equal to half the thickness of the arm 5. The opposite faces 15, 15 of each recess 11 are curved, as shown in Figure 1.

The second U-shaped member 3 has two spaced arms 17, 17 which extend upwardly and have formed therein recesses 19 extending from the outer faces of the arms half-way through the thickness thereof. As shown in Figure 1, the opposed faces 21 of the recesses 19 are curved, and the upper jaw portions 17a of the arms 17 are hook shaped and thereby adapted to engage over the other edge of the lower flange 7 of the girder 9. The arms 5 and 17 are laterally thickened at 23 (Figures 2 and 4), and thus strengthened, at those locations wherein the recesses 11 and 19 are formed.

The arms may be of any suitable length and their hooked upper end portions may be shaped to suit the section of the cross or arch girder 9.

45 During the manufacture of this particular horsehead, the arms 5 and 17 of the members 1 and 3 respectively are so brought together, i. e. by bending, that the portions of the arms at the bottom of the recesses in one member lie in the appropriate recesses in the arms of the other member. The two members 1 and 3 are thus pivotally connected together, with their oppositely inclined pairs of arms crossing each other, and cannot become separated.

55 Whilst, as already described, the upper hooked

end portions of the horsehead are adapted to engage and grip the opposite longitudinal edges of the lower flange 7 of the cross or arch girder 9, the lower horizontal portions or cross-bars of the members are adapted to support a safety or horsehead girder 25. The hooked upper end portions may, if desired, have formed therein a plurality of recesses which are spaced apart along said upper portions and thereby adapted for engagement with cross or arch girders of different sizes.

When it is desired to erect safety or horsehead girders beneath the roof of a coal mine where a mass of coal and other material has been loosened as aforesaid, a number of the horseheads are placed on each of the three or four cross or arch girders of the roadway leading to the coal face or close to a part of the roof of a roadway from which material has been loosened and allowed to fall and safety girders such as 25 are then placed in the horseheads by merely sliding the girders through them. The safety girders are caused to project from the horseheads, nearest the lip or part of the roof from which material has been loosened as far as is possible over the mass of material, and timbers are placed across the projecting portions of the safety girders to support the roof. The weight of the safety girders 25 will tend to force the upper hooked end portions 5a and 17a of the arms 5 and 17 against the girder 9 although, if desired, a ring 27 may, as a precautionary measure, be placed around the lower portions of one arm 5 and one arm 17 to prevent the upper hooked portions of the arms from moving apart and becoming released from the girder 9. The ring 27 is movable upwards to release the members 1 and 3 for movement pivotally and, when permitted, the ring drops to enable it to function with a wedging action suchwise as to lock the said members together.

Instead of fashioning the U-shaped members 1 and 3 from single lengths of material, by bending, each such member may, in the modification illustrated in Figures 5 and 6, be replaced by an equivalent U-shaped member or component of a composite character comprising two initially separate arms in the form of castings which are connected at their lower ends by a rod. In Figures 5 and 6, the two composite members or components are indicated by the numerals 1 and 3—as are the equivalent one-piece members in the previously described example. The member or component 1 has two spaced cast arms 28 which have hooked jaw portions 28a at their upper ends and at their lower ends are bossed to receive the ends of a rod or spindle 29 of circular cross-section whereby they are connected. The ends of the rod 29 are rigidly secured to the arms 28 by means of rivets 30. Similarly, the member or component 3 comprises two cast arms 31 which have hooked jaw portions 31a and are connected by a further rod or spindle 32 secured by rivets at 33. The two composite members or components 1 and 3 are pivotally connected together, with their pairs of arms 28 and 31 being oppositely inclined and crossing each other in precisely the same way as in the first described example: in fact the same reference numerals are used in Figures 5 and 6 to indicate the recesses formed in the arms 28 and 31. Lengths of tubing, constituting rollers 34, are mounted on the rods 29 and 32 to facilitate the movement of a girder (such as 25) through the horsehead. Instead of a ring for preventing the upper hooked

ends of the arms 28 and 31 from moving apart, there is provided, in this modification, a latch member 35 which is fulcrumed at one end upon the connecting rod 32. As shown in Figure 5, the 5 opposite end of the latch member 35 has formed therein a slot 36 of right-angular shape in which the rod 29 of the U-shaped member or component 1 is engaged. The disposition of the slot 36 is such that when, by appropriate manipulation of the member or component 1, the latch member 35 is permitted to drop so that the rod 29 becomes located in the comparatively narrow vertical portion 36a of the slot, the upper portions of the arms 28 and 31 will be prevented from moving apart. Conversely, when the latch member 35 is raised, the rod 29 will be located in the relatively wide horizontal portion 36b of the slot, thereby enabling the upper jaw portions of the arms 28 and 31 to move apart. A washer 37 is 10 interposed between the latch member 35 and the corresponding roller 34.

It will be apparent that the herein described constructional forms of the improved horsehead are of very simple construction, that its two U-shaped members or composite components cannot become separated when it is out of use and that no bolts, screws or the like are required to fix it in position.

A horsehead constructed in either of the ways 15 hereinbefore described may be modified by having two of its inter-engaging arms made longer than the other two arms, thereby enabling the horsehead to support a horizontal girder whilst itself being suspended from an inclined or ring girder.

It will be appreciated that the girder-supporting means hereinbefore described and illustrated in the drawings may be used in connection with girders having cross-sections other than the 'I' section shown, and could even be used in connection with girders which are rectangular in section. Accordingly, wherever the term 'girder' is used in the appended claims it is to be construed as including girders and the like of any convenient cross-section and made of any suitable material.

What I claim then is:

1. A girder-supporting device comprising two U-shaped members each consisting of two initially separate arms which are spaced apart and rigidly connected by a cross spindle, the pair of arms of one member having loose, interfitting pivotal connection with the arms of the other member, one member within the other, and the free ends of the arms remote from the said cross spindles being shaped for engagement with one girder, while the cross spindles are adapted to support another girder suspended from the first mentioned girder, and a freely rotatable roller mounted on each cross spindle, for the purpose 20 of supporting another girder.

2. A girder-supporting device comprising two U-shaped members each having spaced arms connected by a cross portion, the arms of one member crossing and having loose, interfitting pivotal connection with the arms of the other member one member within the other, and the free ends of the arms remote from the cross portions being shaped for engagement with one girder while the aforesaid cross portions are adapted to support another girder suspended from the first mentioned girder, and a ring which embraces the arms of the two members at one side of the device, the said ring being movable upwardly along the said arms to release the 25

members for relative movement downwardly, to prevent movement of the free ends of the arms away from a girder with which they are engaged.

3. A girder-supporting device comprising two U-shaped members each consisting of two initially separate arms which are spaced apart and rigidly connected by a cross spindle, the pair of arms of one member having loose, interfitting pivotal connection with the arms of the other member, one member within the other, and the free ends of the arms remote from the said cross spindles being shaped for engagement with one girder, while the cross spindles are adapted to support another girder suspended from the first mentioned girder, and a latch member which at one end is fulcrumed upon the cross spindle of one of the U-shaped members and at the other end has therein a slot of right angular form through which the cross spindle of the other U-shaped member extends, the said slot having vertical and horizontal portions, and the construction being such that when the latch member is permitted to drop so that the vertical portion of the slot engages over the last mentioned cross spindle, the latch member will function to prevent relative movement of the members, for the purpose specified.

4. A girder-supporting device comprising a U-shaped member consisting of two initially separate arms which are spaced apart and rigidly connected by a cross spindle, the inner faces of the said arms having formed therein opposed recesses, a second similarly constructed U-shaped member in the outer faces of the spaced arms of which are formed further recesses, the said recessed portions of the arms of the two members being loosely interengaged so that the members are capable of relative pivotal movement, and the free ends of the arms of both members being hooked for engagement with and to be supported by a girder while the cross spindles of the U-shaped members are adapted to support a second girder suspended below and transversely with respect to the first girder, freely rotatable rollers mounted on the cross spindles, and a latch member which at one end is fulcrumed upon the cross spindle of one of the U-shaped members and at the other end has therein a slot of right angular form through which the cross spindle of the other U-shaped member extends, the said slot having vertical and horizontal portions, and the construction being such that when the latch member is permitted to drop so that the vertical portion of the slot engages over the last mentioned cross spindle, the latch member will function to prevent relative movement of the members, for the purpose specified.

5. A supporting appliance comprising a pair of end frames, each frame being constituted by a

pair of crossed arms recessed between their ends and formed for fulcruming and loose interengagement in these recesses, means rigidly interconnecting the outer arms and rigidly interconnecting the inner arms, respectively, of the two frames at the lower end parts of these arms to maintain the appliance assembled, said arms being formed at their upper ends with jaws for engagement with a support, whereby a member placed on the interconnecting means of the two sets of arms will be carried slung from this support.

6. A supporting appliance as defined in claim 5, wherein each of said arms is formed to project laterally outwards at the position of the fulcrum recess therein so as to be of substantially uniform transverse cross-sectional area throughout its length.

7. A supporting appliance as defined in claim 5, wherein the recess in each arm is defined at opposed ends by curved faces.

8. A supporting appliance comprising a pair of end frames, each frame being constituted by a pair of crossed arms recessed between their ends and formed for fulcruming and loose interengagement in these recesses, and means rigidly interconnecting the outer arms and rigidly interconnecting the inner arms, respectively, of the two frames at the lower end parts of these arms to maintain the appliance assembled, and means for limiting the opening apart of the lower ends of the frames, said arms being formed at their upper ends with jaws for engagement with a support, whereby a member placed on the interconnecting means of the two sets of arms will be carried slung from this support.

9. A supporting appliance comprising a pair of end frames, each frame being constituted by a pair of crossed arms, recessed between their ends and formed for fulcruming and loose interengagement in these recesses, and separable cross spindles rigidly interconnecting the outer arms and the inner arms respectively of said frames at the lower ends of these arms, said arms being formed at their upper ends with jaws for engagement with a support, whereby a member placed on the cross spindles of the two sets of arms will be carried slung from this support.
